UNITED STATES PATENT OFFICE.

ALBERT E. JONES, OF MARYVILLE, TENNESSEE.

DESIGN FOR A HAT-RACK.

46,678.

Specification for Design. Patented Nov. 24, 1914.

Application filed August 13, 1914. Serial No. 856,687. Term of patent 14 years.

To all whom it may concern:

Be it known that I, ALBERT E. JONES, a citizen of the United States, residing at Maryville, in the county of Blount and State of Tennessee, have invented a new, original, and ornamental Design for a Hat-Rack, of which the following is a specification, reference being had to the accompanying drawing, forming a part thereof.

The figure is a side elevation of a hat rack embodying my invention.

I claim:

The ornamental design for a hat rack, as shown.

ALBERT E. JONES.

In the presence of—

MILLE A. MCTEED,

R. R. KRAMER.
